[57] CLAIM

The ornamental design for a soft-sided food and beverage container, as shown and described.

DESCRIPTION

FIG. 1 is a top, rear, and right side perspective view of a soft-sided food and beverage container showing my new design;

FIG. 2 is a top plan view thereof;

FIG. 3 is a left side elevational view thereof, the right side elevational view being a mirror image of the left side elevational view;

FIG. 4 is a rear elevational view thereof;

FIG. 5 is a front elevational view thereof; and,

FIG. 6 is a bottom plan view thereof.
